CLAIM

The ornamental design for a glove, as shown and described.

DESCRIPTION

FIG. 1 is a top perspective view of a left hand glove showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front, left perspective view thereof; and,

FIG. 7 is a rear perspective view thereof.

The broken lines shown in the drawings form no part of the claimed design. The glove can be made of flexible materials.

1 Claim, 7 Drawing Sheets
